UNITED STATES PATENT OFFICE.

ERNEST SCHMALE, OF BELLEVILLE, ILLINOIS.

DESIGN FOR A STOVE BRACKET OR SIMILAR ARTICLE.

Application filed April 12, 1923. Serial No. 5,801. Term of patent 3½ years.

To all whom it may concern:

Be it known that I, ERNEST SCHMALE, a citizen of the United States, residing at Belleville, in the county of St. Clair and State of Illinois, have invented a new, original, and ornamental Design for Stove Brackets or Similar Articles, of which the following is a specification, reference being had to the accompanying drawing, forming part thereof.

Figure 1 is a perspective view of a bracket, showing my new design, and

Figure 2 is an edge view of the bracket.

I claim:—

The ornamental design for a stove bracket or similar article, as shown.

ERNEST SCHMALE.
